(57) **CLAIM**

The ornamental design for bracelet clasp positioning device, as shown and described.

DESCRIPTION

FIG. 1 is a perspective view of a bracelet clasp positioning device showing my new design;

FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof; and,

FIG. 8 is a perspective view showing the support stand, clasp, and a bracelet in broken lines.

The broken lines shown in the drawings represent portions of the support stand, clasp, and bracelet that form no part of the claimed design.
